UNITED STATES PATENT OFFICE.

WILBUR DAVIS, OF COLLINS, IOWA.

EGG CANDLING AND HANDLING DEVICE.

1,407,191.

Specification of Letters Patent. Patented Feb. 21, 1922.

Application filed May 23, 1921. Serial No. 471,899.

To all whom it may concern:

Be it known that I, WILBUR DAVIS, a citizen of the United States, and a resident of Collins, in the county of Story and State of Iowa, have invented a certain new and useful Egg Candling and Handling Device, of which the following is a specification.

The object of my invention is to provide an egg candling and handling device of simple, durable and inexpensive construction.

More particularly, it is my object to provide such a device whereby an entire filler containing thirty-six eggs (the usual number) may be properly manipulated for candling the eggs in the filler.

Still a further object is to provide a transparent filler having fingers so arranged and mounted thereon that the holder may be moved downwardly from above into proper position with relation to the filler, so that the entire filler may be taken from the egg case at one time, inverted and placed in a candling device with the transparent member down, so that the entire thirty-six eggs may be examined in the filler.

A further object is to provide in connection with such a filler holder or support, a transparent member, having fingers held thereon by resilient gripping elements.

Still a further object is to provide such a device including the filler holder and an egg case, having two adjacent sides mounted to be moved out of the way during the candling operation.

With these and other objects in view, my invention consists in the construction, arrangement and combination of the various parts of my device, whereby the objects contemplated are attained, as hereinafter more fully set forth, pointed out in my claims, and illustrated in the accompanying drawings, in which:

Figure 1 shows a perspective view of the egg case.

Figure 2 shows a vertical, transverse, sectional view through the same and through the filler engaging and holding member, the latter being in its inverted position.

Figure 3 shows a detailed, sectional view taken on the line 3—3 of Figure 2.

Figure 4 shows a perspective view of the resilient fingers device; and

Figure 5 shows a perspective view of the candling mechanism with the filler support in position thereon.

It has heretofore been quite difficult to

candle a considerable number of eggs at a time in a satisfactory way. It has therefore been my purpose in working out my present device to provide means whereby an entire 60 filler, holding for instance three dozen eggs, may be removed from a case in an easy and convenient way and supported on a transparent holder or support in such a way that the entire three dozen eggs received in the 65 filler may be candled in one operation.

In accomplishing such a purpose, it is necessary to have a case, two sides of which (or a top and one side) may be swung open so as to allow access to the fillers and also 70 to provide a transparent holder having fingers or the like adapted to be readily and easily slid between the edges of the flats and the case.

In the accompanying drawings, I have 75 used the reference numeral 10 to indicate generally an egg case having a top 11, which may be hinged at one end or removable, and having a side 12, which is also either hinged or removable. The case shown has a central 80 transverse partition 13.

On the opposite sides of the partition are the tiers of fillers 14 separated by flats 15.

In Figure 5, I have shown a candling device comprising a supporting casing 16, 85 which is designed to have an electric light bulb or other source of light mounted therein. The casing 16 has a shelf or the like 17 shown in dotted lines around the walls thereof on the inside, and one wall is opened 90 above the shelf.

I provide a special transparent device for supporting a filler full of eggs, which comprises a transparent sheet or pane 18, which is longer at one side, and is designed to be of 95 sufficient width to fit snugly within one-half of the egg case 10 with one end projecting therefrom. The projecting end of the transparent plate 18 forms a handle.

At the end of the plate 18 opposite the 100 handle is a series of engaging fingers 19, preferably of flat sheet metal or the like, secured to a resilient channel 20. The channel 20 has its side walls so arranged that they tend to spring together, and in the 105 construction of my device the end of the plate 18 opposite the handle end is slipped between the walls of the channel 20, as shown in Figure 2, with the plate snugly and frictionally gripped between the walls 110 of said channel, and with the fingers 19 projecting at right angles from the plate.

At each side of the plate 18, I provide one or more fingers 22, which are frictionally held on the plate 18 by means of resilient gripping fingers 23.

- 5 In the practical use of my device, after the top 11 and sides 12 have been opened, the operator grasps the plate 18 by the handle end thereof, turns the plate over to substantially the position shown in Figure 2, 10 and slips the plate downwardly from above to position adjacent to the first filler of eggs, after the flat above the filler has been removed. The fingers 19 are slipped behind the filler and the fingers 22 slide alongside 15 the filler between the walls of the case 10 and the filler.

The filler with the eggs therein and with the next lowermost flat is then pulled out a short distance, whereupon the operator 20 grasps the flat, so as to hold the eggs against falling out, and pulls out the filler with the flat below it.

The filler and plate 18 are then turned over with the filler up and the flat is removed from the top of the filler, whereupon the plate 18 may be slid onto the shelf 17 in the candling device 16, and the eggs in the filler may then be examined in the usual way.

30 After the eggs have been examined, the plate 18 is removed from the casing 16, the flat is placed on top of the filler, and the filler and flat and the plate 18 are then inverted again, and the filler full of eggs with 35 the plate thereunder may be slipped into the egg case 10.

The fingers 22 may be adjusted longitudinally of the plate 18 by sliding the gripping fingers 23, and will be held in any 40 adjusted position.

It is obvious that in order to make the device properly operative, the fingers 22 and 19 should be thin and flat and that there should be no other projections on the plate 45 18.

It will be seen that my device is of very simple and inexpensive construction and that by means of it, eggs can be candled in

the fillers very rapidly and without danger of breakage.

I have found by testing that a transparent plate 18 is much better than one which has a series of holes therein. A transparent plate also has a flat surface, so that there is less movement of the eggs in the 55 filler, where my device is used, than where a plate having holes is employed.

Some changes may be made in the construction and arrangement of the various parts of my device, and it is my intention 60 to cover by my claims, any modified forms of structure, or use of mechanical equivalents, which may be reasonably included within their scope.

I claim as my invention:

1. In a device of the class described, the combination of an egg case, having two sides capable of being removed for permitting access to the interior of the case with a transparent plate longer than the egg filler used 70 in such case, said plate having at one end and at its sides fingers projecting at right angles from the plate and adapted to be inserted at the three sides of the filler between the filler and the walls of said case 75 by a movement directly downwardly in the case from the top toward the bottom thereof.

2. In a device of the class described, the combination of an egg case, having two 80 sides capable of being removed for permitting access to the interior of the case, with a transparent plate longer than the egg filler used in such case, said plate having at one end and at its sides, fingers 85 projecting at right angles from the plate and adapted to be inserted at the three sides of the filler between the filler and the walls of said case by a movement directly downwardly in the case from the top toward the 90 bottom thereof, resilient gripping elements for holding said fingers frictionally on said plate.

Des Moines, Iowa, May 12, 1921.

WILBUR DAVIS.
